CLAIM

The ornamental design for an combined insect repellent and sunscreen applicator as shown.

DESCRIPTION

FIG. 1 is a frontal isometric view of my combined insect repellent and sunscreen applicator, showing my new design; FIG. 2 is a lower isometric view thereof;

FIG. 3 is top plan view thereof;

FIG. 4 is a bottom plan view thereof;

FIG. 5 is a side elevational view thereof; and,

FIG. 6 is a bottom plan view of the combined insect repellent and sunscreen applicator shown in a new configuration with the sponge removed.

The dashed lines in FIGS. 2, 4, and 6 show environment only and form no part of the claimed design.

1 Claim, 4 Drawing Sheets
